UNITED STATES PATENT OFFICE.

HOWARD E. BURNS, OF ST. LOUIS, MISSOURI.

RAILWAY-CROSSING.

1,191,561.

Specification of Letters Patent. Patented July 18, 1916.

Application filed February 17, 1916. Serial No. 78,915.

To all whom it may concern:

Be it known that I, HOWARD E. BURNS, a citizen of the United States, residing at St. Louis, Missouri, have invented a certain new 5 and useful Improvement in Railway-Crossings, of which the following is a full, clear, and exact description, such as will enable others skilled in the art to which it appertains to make and use the same.

10 This invention relates to railway crossings.

The crossings that are now in general use in rural districts are formed from heavy planks which are spiked directly to the track 15 ties.

One objectionable feature of a crossing of the type mentioned is that it cannot be taken up and relaid without liability of destroying some or all of the planks that constitute the crossing, owing to the fact that the planks are held in position by large spikes which generally cannot be withdrawn without splitting or damaging the planks. As it is necessary to take up some crossings 20 frequently to keep the track in repair, and as one or more of the planks are generally destroyed every time said crossings are taken up, the cost of maintenance of plank crossings is very high. Furthermore, considerable time and labor is required to install a plank crossing, and as the planks soon rot or decay, the life of a plank crossing is generally only a few years. Solid concrete 25 crossings are sometimes used at the intersection of a railway track and a paved road or street, but a solid concrete crossing is very expensive to install, and as it forms a "hard spot" in the track, the track rails are liable to break when they are subjected to the load of a passing train. Attempts have 30 been made to form a permanent crossing, by laying bricks or other hard paving material on the bed of the track, but such crossings have not proved satisfactory on account of the fact that the movement produced in the bed of the track by a passing train or by a frost causes the bricks or other hard paving material to work loose and break up.

35 One object of my invention is to provide a railway crossing that is more durable than a plank crossing and which is so constructed that it can be taken up and relaid easily and without liability of injuring or 40 destroying the crossing.

Another object is to provide a permanent railway crossing that will not interfere with the natural wave motion of the track rails or be affected by movement in the bed of the track produced by a passing train or by 45 a frost.

Another object is to provide a permanent railway crossing that can be laid directly on the track ties that support the rails. And still another object is to provide a permanent crossing that can be built and installed at the same cost, or a lower cost, than a plank crossing and which can be taken up and relaid in less time than a plank crossing.

50 Other objects and desirable features of my invention will be hereinafter pointed out.

Briefly stated, my invention consists in a railway crossing composed of a number of 55 durable members combined in such a manner that they produce a flexible roadway which is not affected by movement in the bed of the track or movement of the track rails. The members that constitute the 60 crossing are combined in such a manner that the entire crossing, or a portion of it, can be taken up and relaid quickly, and in the preferred form of my invention, as 65 herein shown, the said members consist of 70 oblong-shaped blocks that are held together by a means which permits said blocks to move independently of each other sufficiently to impart to the complete crossing 75 a certain degree of flexibility longitudinally 80 of the track and transversely of the track. It is immaterial, so far as my broad idea is concerned, what the members constituting 85 the crossing are formed of, so long as they are 90 formed of material that is capable of successfully 95 withstanding great wear and hard usage, and while I have herein illustrated several ways of connecting said members 100 together, I wish it to be understood that my invention is not limited to a railway crossing 105 of the particular construction herein illustrated.

Figure 1 of the drawings is a top plan view of a railway crossing constructed in accordance with my invention. Fig. 2 is a longitudinal sectional view of said crossing, taken on the line 2—2 of Fig. 1. Figs. 3 and 4 are transverse sectional views, taken on the lines 3—3 and 4—4 of Fig. 1; and Figs. 5 and 6 are transverse sectional views, 110.

2
illustrating slight modifications of my invention.

- The crossing shown in Figs. 1 to 4, inclusive, is composed of a number of oblong-shaped blocks A, preferably formed from reinforced concrete, as shown in Fig. 4, although said members A can, of course, be formed from any other suitable material without departing from the spirit of my invention. The members A are mounted on the track ties 1 in parallel relation to the track rails 2 and in transverse alignment with each other, as shown in Fig. 1, thus forming a number of parallel longitudinal sections, each of which is made up of a plurality of short blocks A. The blocks A are preferably made long enough so that each block will rest upon two track ties, and the blocks that constitute each separate longitudinal section of the crossing are connected together in such a manner that they can move vertically slightly with relation to each other, but cannot separate or pull apart longitudinally. The various longitudinal sections of the crossing are also preferably connected together in such a manner that said sections cannot separate laterally, and the entire structure is anchored to the rails or to the track ties so as to prevent it from moving bodily with relation to the ties on which it rests. One convenient way of connecting the blocks or members A constituting one longitudinal section together is shown in Fig. 1, wherein the reference character 3 designates long rods or bolts, each of which passes through a plurality of blocks A that are arranged in longitudinal alignment with each other, the crossing shown in Fig. 1 comprising seven longitudinal sections, five of which are arranged between the two rails and the remaining sections being arranged outside of the rails. The blocks A are provided with holes 4 through which the rods 3 pass, and the diameter of the hole 4 in each block is great enough to permit the block to move slightly in a vertical direction with reference to the rod 3 that passes through said hole. Consequently, if one or more of the track ties drops slightly, due to displacement of the bed of the track, the blocks or members A that rest on said ties can move downwardly with relation to the remaining blocks A of the crossing. Likewise, if one or more of the track ties move upwardly, due to displacement of the bed of the track, the blocks A supported by said ties will move upwardly with relation to the remaining blocks of the crossing.
- The means shown in Figs. 1 to 4 for tying the various longitudinal sections of the crossing together consists of a plurality of transversely-disposed bars 5 that are arranged between the abutting ends of the blocks A and which are provided with open-

ings 5^a through which the longitudinally-disposed rods 3 pass, the ends of said bars 5 preferably fitting between the heads and the base flanges of the track rails 2, as shown in Fig. 3, so as to prevent the crossing from moving bodily upwardly off the track ties 1. The two longitudinal sections that are arranged outside of the track rails are connected to the portion of the crossing that lies between the rails by means of short bars 6 that pass downwardly underneath the base flanges of the rails, as shown in Fig. 3, said bars 6 having openings for receiving the longitudinally-disposed bolts 3 that pass through the blocks of the two sections of the crossing that lie adjacent each of the rails 2. Spacing devices 7, which are preferably formed of wood, are arranged between the ends of the transversely-disposed bars 5, so as to hold said bars in parallel relation, the advantage of forming the spacing devices 7 from wood being that they can be cut off easily during the operation of installing the crossing so that they will fit snugly between the end of a rail joint or angle bar 8 and the cross bar 5 that is arranged adjacent the rail joint, as shown in Fig. 1. If desired, each of the blocks A may be provided on one of its longitudinal edges with a rib 9 and on its other longitudinal edge with a groove 10, so that when the blocks are arranged in operative position the blocks in the various longitudinal sections of the crossing will be interlocked with each other, but this is not essential to the successful operation of my crossing.

A crossing of the construction above described is durable and can be used for a long period, as it is made up of members formed from concrete or other suitable material that is capable of successfully withstanding great wear and rough usage. It can be installed easily and it can be taken up and relaid without liability of damaging or destroying any of the members A that make up the crossing; if it becomes necessary to raise one of the rail joints or repair one portion of the track, this can be accomplished easily by taking up only one or two sections of the crossing, it being possible to remove any section of the crossing by withdrawing the longitudinal rod 3 on which the members A constituting said section are strung. The crossing is flexible enough so that it will not interfere with the natural wave motion of the track rails, and another desirable feature that results from this characteristic of the crossing is that all portions of same will rise or fall with the bed of the track, and thus prevent any portion of the crossing from being unsupported at any time. In other words, the members A that constitute the crossing are tied together in such a manner that they cannot pull apart or separate,

but nevertheless, said members are free to rise and fall with the track ties on which they rest, thereby eliminating the possibility of the crossing being disrupted by an upheaval of the bed of the track, or from being broken by a heavy load passing over a portion of the crossing from which the bed of the track had receded, as might occur if the crossing was composed of members rigidly connected together.

While I prefer to fill the entire space between the track rails with members A, this is not essential, as a good crossing can be made by arranging two longitudinal sections 15 in proximity to each rail, as shown in Fig. 5, each longitudinal section being made up of a plurality of blocks or members A', strung on longitudinally-disposed rods 3^a, and the two sections on the opposite sides 20 of each rail being tied together by cross bars 6^a that pass downwardly underneath the base flange of the rail in practically the same manner as the cross bar 6 of the crossing shown in Figs. 1 to 4, the space between the 25 two inner longitudinal sections being filled with track ballast, or any other suitable material.

In Fig. 6 I have illustrated still another form of my invention, wherein the various 30 longitudinal sections of the crossing are tied together by cross bars 11 that pass through eyes in devices 12 which project downwardly from the undersides of the members A, said devices 12 either passing through 35 holes in said members or being permanently embedded in the members A, if said members are formed from concrete or other plastic material that can be molded into shape. A railway crossing of the construction above 40 described is more durable than a plank crossing and it can be maintained at a much lower cost than a plank crossing, owing to the fact that the entire crossing, or any portion of same, can be taken up and relaid 45 without liability of injuring or destroying the members that form the crossing; it is as durable as a solid concrete crossing and can be installed at a much lower cost than a solid concrete crossing, and as it does not 50 form a "hard spot" in the track, it does not cause the track rails to break. Such a crossing is also a decided improvement on a brick crossing or crossing composed of other permanent road materials, owing to the fact 55 that it is so constructed that displacement of the bed of the track has absolutely no effect on the crossing and it will not disrupt same. A crossing of the character herein illustrated, when made of concrete blocks, can 60 be manufactured and installed at as low a cost as a plank crossing, owing to the fact that the labor of installing the crossing is considerably less than installing a plank crossing; the crossing presents a neat and 65 ornamental appearance; it is particularly

well adapted for use on a curved track and its cost of maintenance is very low, on account of the fact that it is built up of small units that can be replaced easily.

While I prefer to run a rod or cable 70 through the members that make up one longitudinal section of the crossing, it is not essential that the members constituting each longitudinal section be connected together in this particular manner, so long as said members are prevented from pulling apart endwise. For example, the members A that are arranged in transverse alignment with each other can be connected together in the manner illustrated in Fig. 6, or in any other suitable way, and means can be arranged at the ends of the crossing to prevent the members A from shifting longitudinally of the track. The same result could be accomplished by coupling the members of the outside longitudinal sections together and holding the intermediate longitudinal sections in position by means of the cross rods 11 shown in Fig. 6.

When the crossing is made very long, one or more portions of the crossing are constructed in such a manner that they can be taken up so as to permit the longitudinally-disposed tie rods or cables 3 to be withdrawn. For example, in a long crossing one portion of same could be made up of a number of members A arranged in transverse alignment with each other and connected by a cross rod 11, as indicated in Fig. 6, the portions of the crossing lying on opposite sides of same being made up in the manner illustrated in Figs. 3 and 4. By withdrawing the cross rod 11, one set of blocks A extending transversely of the track could be taken up and thereafter the longitudinal bolts 3 in the other portions of the crossing could be withdrawn. As previously stated, however, it is immaterial how the various members constituting the crossing are connected together, so long as they are combined in such a manner that they can move sufficiently with relation to each other to impart more or less flexibility to the crossing.

Having thus described my invention, what I claim, and desire to secure by Letters Patent, is:

1. A railway crossing, composed of a number of members loosely connected one with another in such a manner that they are free to move slightly in a vertical direction with relation to each other without separating or pulling apart.

2. A railway crossing, composed of a plurality of rigid members connected together in such a manner that they form a flexible roadway whose road surface members are free to move relatively to each other in a certain way without pulling apart.

3. A railway crossing, composed of a plu-

4

rality of rigid members permanently connected one with another in such a manner that they do not interfere with the natural wave motion of the track rails.

5. 4. A railway crossing, composed of a plurality of durable members connected with each other in such a manner that they form longitudinally-disposed sections, each of which can flex slightly intermediate the ends of same.

10 5. A railway crossing, composed of a plurality of durable, rigid members loosely connected together in such a manner that the crossing as an entirety has sufficient flexibility to conform approximately to the bed of the track on which it is mounted without liability of said members becoming deranged or separated.

15 6. A railway crossing, composed of a plurality of members arranged end to end and divided by joints that extend transversely of the track, each member being connected to the members arranged at the ends of same in such a manner that any member can move slightly in a vertical direction without breaking away from the other members constituting the crossing.

20 7. A railway crossing, composed of a plurality of members divided by joints that extend transversely and longitudinally of the track, and means that connects one member to the two members arranged at the ends of same and permits said members to move slightly with relation to each other without disrupting the crossing.

25 8. A railway crossing, composed of a plurality of rigid and durable members, certain ones of which are joined directly together and all of which are combined with the road bed in such a manner that the crossing as an entirety has sufficient flexibility to prevent it from being disrupted by natural movement of the bed of the track.

30 9. A railway crossing, composed of a plurality of relatively short members, each of which is jointed to the members arranged at the ends of same and all of which are combined with a means that prevents the crossing as an entirety from moving vertically with relation to the track rail.

35 10. A railway crossing, consisting of a skeleton-like metal structure and a road surface formed from members that are combined with said structure in such a manner that said members can move upwardly and downwardly slightly with relation to each other and also with relation to said structure.

40 11. A railway crossing, composed of a plurality of members that form a roadway over a track, and a skeleton-like metal structure that retains said members in position and joins each member to the members between which it is arranged.

45 12. A railway crossing, comprising a plu-

rality of members arranged end to end in a direction extending longitudinally of the track, and means that directly joins said members one to another and permits any member to move slightly upwardly or down- 70 wardly.

13. A railway crossing, comprising a plurality of road surface members having aligned holes that extend longitudinally of the track, and a device that passes through said holes and joins said members together.

14. A railway crossing, comprising two longitudinal sections arranged on opposite sides of one rail of the track and each composed of a plurality of members joined together by a means which permits the section as an entirety to have a certain degree of flexibility, and means for preventing said sections from moving laterally away from the track rail.

15. A railway crossing, comprising two longitudinal sections arranged on opposite sides of one rail of the track and each composed of a plurality of comparatively rigid members joined together in such a manner that the section as an entirety can flex intermediate its ends, and means that ties said sections together and holds them in proper position with relation to the track rail.

16. In a railway crossing, a pair of longitudinal sections arranged on opposite sides of one rail of the track and each composed of a plurality of members arranged end to end, rods extending longitudinally through the members of each section, and cross bars 100 connected to said rods and passing downwardly beneath the track rails so as to prevent said sections from being displaced with reference to said track rails.

17. A railway crossing, comprising a plurality of transversely-disposed bars arranged in engagement with the track rails, longitudinally-disposed rods passing through openings in said bars, and members mounted on said rods between said bars to 110 form a roadway over the track.

18. A railway crossing, comprising a plurality of transversely-disposed bars arranged in parallel relation and having their opposite ends fitting between the base flanges 115 and the heads of the track rails, longitudinally-disposed rods that pass through openings in said bars, and members strung on said rods to form a roadway over the track.

19. In a railway crossing, track ties, a plurality of members mounted on said ties that form a roadway, and means that joins certain of said members directly together but permits them to move vertically slightly 125 with relation to each other without disrupting the crossing.

20. A railway crossing, comprising a plurality of longitudinal sections, each of which is composed of a plurality of members 130

joined together in such a manner that the section as an entirety is free to flex slightly intermediate its ends, and means that ties said sections together.

- 5 21. A railway crossing, comprising a plurality of longitudinal sections, each of which is composed of a plurality of members joined together in such a manner that the section as an entirety is free to flex slightly intermediate its ends, and means for tying said sections together and for preventing the crossing as an entirety from moving upwardly with relation to the track rails.
- 10 22. In a railway crossing, track ties, members resting upon said track ties and sepa-

rated by joints that extend transversely of the track, and rods extending longitudinally of the track and passing through holes in said members which are of sufficient diameter to permit any member to move slightly 20 with relation to the rod on which it is mounted.

In testimony whereof I hereunto affix my signature in the presence of two witnesses, this fifteenth day of February 1916.

HOWARD E. BURNS.
